UNITED STATES PATENT OFFICE.

WILLIAM J. GRIBBIN, OF WASHINGTON, DISTRICT OF COLUMBIA.

LANSTON MONOTYPE PERFORATING MACHINE.

Application filed March 29, 1920, Serial No. 369,574. Renewed June 20, 1924.

To all whom it may concern:

Be it known that I, WILLIAM J. GRIBBIN, a citizen of the United States of America, and a resident of the city of Washington, 5 District of Columbia, have invented certain new and useful Improvements in Lanston Monotype Perforating Machines, of which the following is a full and clear specification.

10 This invention has relation to the well-known Lanston monotype perforating machine. In this machine, the unit-wheel is rotated in opposite directions by a pair of opposed cylinders adapted to receive compressed air, one of the pistons of these cylinders being at all times, while the machine is in operation, under air pressure. There are certain times when it is desirable or necessary to rotate the unit-wheel directly or by 15 intermediate manual mechanism. This operation is quite laborious for operatives who have but little physical strength, and it is the object of the present invention to provide means whereby this operation may be 20 quickly and easily accomplished without the exertion of any material degree of physical strength, to thereby permit this operation to be performed by operatives who would find it fatiguing and difficult to operate the unit-wheel against the air-pressure in the cylinders.

In the drawing—

Fig. 1 is a partial plan and partial sectional view of a portion of a Lanston perforating machine showing my invention applied thereto;

Figs. 2, 3 and 4 are detail views herein-after described.

In the drawing, *a* designates the usual 40 unit-wheel which is rotated first in one direction and then in the other by means of a pinion *b* attached to a shaft and a rack *c* which is reciprocated alternately in opposite directions by means of restore-cylinder *d* at one side and the driving-cylinder *e* at the other side, the shaft of said unit-wheel being also provided with a pinion *f* which drives the usual rack *g* carrying the scale-pointer *h*, these parts operating in the usual well-known manner.

The inlet-end of the cylinders *d* and *e* are connected by a pair of conduits *i* with a valve-chamber *j* formed in the piston-block of the machine, said conduits being partially shown in dotted lines. The 55 valve-chest *j* is constantly supplied with air under pressure through a conduit *h* in the

usual manner. The usual reciprocating valve *l* is employed for alternately venting the conduits *i*, this valve being, as usual, under the control of the keyboard devices, not 60 shown. By reciprocating the valve *l*, it will be understood that the cylinders *d* and *e* are alternately connected with the air-supply, to thus drive their respective pistons in opposite directions. In certain operations of the machine, while air pressure is in cylinder *e*, the unit-wheel must be rotated manually against the air pressure in said cylinder *e*. This operation is a fatiguing one for physically weak operatives. 65 To free this cylinder *e* from air pressure and thus permit the unit-wheel to be operated by hand without fatigue, I provide a valve device in the supply-conduit *k*, just where it enters the valve-chamber *j*. This valve device is in the form of a rotary plug *m* provided with a transverse passage *n* which is adapted by rotation of the plug to be brought into alignment with the conduit *k*, to thus permit air to enter the valve-chamber *j* 70 during the regular operation of the machine. When it is desired to vent the driving-cylinder *e*, this plug *m* is given a quarter turn to thus close the port *n* and bring into communication with the valve-chamber *j* a port *o* 75 formed longitudinally of the exterior of the plug *m*. This port *o* extends to the outer end of the plug and vents to the atmosphere, thereby relieving the driving-cylinder *e* of pressure, thus permitting the unit-wheel and 80 its connected mechanism to be operated without fatigue. When the proper adjustment of the unit-wheel mechanism is made, the usual pawl that holds this unit-wheel against rotation is allowed to re-engage and thus 85 lock the unit-wheel, and then the valve *m* is rotated back to normal position to thereby readmit air to the driving-cylinder.

Any suitable means may be provided for 90 rotating the plug-valve *m*. I show an arm *p* affixed to the shaft of the plug and pivotally connected to a push-and-pull-rod *q* by means of a lug *r*, the rod *q* being supported in any suitable manner in a position convenient for 95 operation.

In the perforating machines now in use, there is located at the side of the piston-block opposite the air-chamber *j* and its valve a similar chamber and valve connected in a similar manner with an air-supply 100 source and by ports with the paper-feed mechanism. It has been found at times in 105

the operation of the machine that it is necessary to stop the feed of the paper; by inserting a valve similar to valve *m* in a like position in reference to the paper-feed valve 5 I am able to cut off the supply of air to the paper-feed mechanism and vent the chamber and its connections to the atmosphere, thereby stopping the feed of the paper.

The nature and scope of the invention 10 having been thus indicated and its preferred embodiment having been specifically described, what is claimed as new is:

1. In a perforating machine of the Lan-
ston pneumatic type, embodying an air-sup-
ply-conduit, a reversing valve and cylinders
15 for driving the unit-rack, a valve inserted in
the air-supply-conduit between the source of
pressure and the reversing-valve, said valve
being adapted to close said supply passage

and to simultaneously vent the valve-cham-
ber and the unit-rack driving cylinders, for
the purpose set forth.

2. In a perforating machine of the Lan-
ston pneumatic type, the combination with
a piston-block having an air-chamber con-
nected to the source of supply of air and air-
ports connected to an operating mechanism
25 of the machine, and a valve in said air-cham-
ber for alternately closing and opening said
air-ports from the air-supply source, of a
separate manually-operated valve positioned
30 between said air-supply source and said air-
chamber for cutting off the supply of air
from the source and venting said chamber
to the atmosphere.

In testimony whereof I hereunto affix my
signature.

WILLIAM J. GRIBBIN.
